No. 12,611

Dec. 20, 1881

UNITED STATES PATENT OFFICE.

H. CLAY BASCOM, OF TROY, AND TOBIAS S. HEISTER, OF LANSINGBURG,
NEW YORK, ASSIGNORS TO N. S. VEDDER PATTERN WORKS, BASCOM,
GALBRAITH & CO., OF TROY, NEW YORK.

DESIGN FOR A STOVE.

SPECIFICATION forming part of Design No. 12,611, dated December 20, 1881.

Application filed November 21, 1881. Term of patent 7 years.

To all whom it may concern:

Be it known that we, H. CLAY BASCOM, a citizen of the United States, residing in the city of Troy, in the county of Rensselaer and State of New York, and TOBIAS S. HEISTER, a citizen of the United States, residing in the village of Lansingburg, in said county and State, have jointly invented and produced a new and original Design for Cooking-Stoves, of which the following is a specification, reference being had to the accompanying cut, print, or engraving of a stove having said new design.

The design for the panel ornament A consists of the four triangular segments *a*, all radiating in diametrically-opposite pairs from a common center, and each having the angle *b* projecting from its outer side, and a face ornament, *c*, and the ornamented segments *d* between the said triangular segments, and of less radial extent than the latter, and the whole being shaped, proportioned, and combined substantially as shown in the accompanying print.

The design for the door-panel B consists of the diagonally-opposite compound corner ornaments, *e f*, and the intermediate diagonal band, *g*, having parallel sides, and formed with the vine ornament *h*, all composed, shaped, and arranged substantially as shown in the accompanying engraving, irrespective of the flower-branch ornament *i* on said panel.

The design for the oven-door consists of the outer convex border-molding, *j*, the panel B, ornamented as above described, and the panel ornament A, composed as above specified, and all arranged in combination substantially as shown in the aforesaid cut.

The design for the small door C and panel D consists of the convex outer molding, *k*, diagonally-opposite corner ornaments, *l m*, central ornament, *n*, and diagonal band *o*, all shaped and arranged substantially as shown in the aforesaid cut.

The design for the closet-door E consists of the central compound ornament, *p*, diagonal band *q*, and diagonally-opposite corner ornaments, *r s*, all shaped and arranged together substantially as shown in the aforesaid engraving.

50 The design for the base-sides F consists of the ornamenteally-curved and angular outline

of the lower edge, *t*, the middle radial ornament, *u*, right and left vine ornaments *v v'*, and end ornaments, *v'*, all shaped and arranged together substantially as shown in the aforesaid print.

The design for the base-corners consists of the rectangular panel *w*, curved horizontally, and having the diagonal vine-ornamented belt *x* and the diagonally-opposite corner ornaments, *y*, all shaped and arranged together substantially as shown in the aforesaid cut.

The design for the legs consists of the diagonal vine-ornamented belt *z*, upper corner ornament, *z'*, and lower end ornament, *z''*, on the swelled surface *z''*, having ornamental edges *z''*, all shaped and arranged substantially as shown in the aforesaid engraving.

What we claim as our joint invention is—

1. The design for the panel ornament A, consisting of the parts *a b c*, and *d*, all shaped and combined as shown and described.

2. The design for the panel B, composed of the parts *e f g h*, all shaped and arranged as set forth.

3. The design for the oven-door, consisting of the combination of the ornament A, composed as described, panel B, ornamented as specified, and the border-molding *j*, as set forth.

4. The design for the small door C and panel D, composed of the parts *k l m n o*, all shaped and arranged as set forth.

5. The design for the closet-door E, consisting of the parts *p q r s*, all shaped and arranged as set forth.

6. The design for the base-sides F, composed of the ornamental parts *t u v v'*, all shaped and arranged as described.

7. The design for the base-corners, composed of the parts *w x y*, all shaped and arranged as set forth.

8. The design for the legs, consisting of the parts *z z' z'' z''*, all shaped and arranged as described and shown.

In testimony whereof we hereunto set our hands, in the presence of two subscribing witnesses, this 19th day of November, 1881.

H. CLAY BASCOM.

TOBIAS S. HEISTER.

Witnesses:

AUSTIN F. PARK,

JAMES T. GOODFELLOW.
